3 Claims. (Cl. 196—52)

This invention deals with the operation of a pneumatic lift used for elevating granular contact material from a given location to a higher location. It is particularly concerned with a method of operating such a lift in continuous hydrocarbon conversion processes in which granular contact material is moved through conversion and reconditioning zones in a closed cyclic path.

The invention may be applied to such processes as catalytic cracking, isomerization, hydrogenation, dehydrogenation, reforming, hydroforming, aromatization, alkylation, ciclicization treating or desulfurization of petroleum fractions. Also, the invention may be applied to coking of hydrocarbons in the presence of granular coke or refractory solids, viscosity reducing of petroleum residues at elevated temperatures, pyrolytic conversion processes such as the conversion of propane and ethane to unsaturated hydrocarbons and of methane to acetylene.

The contact material involved may vary widely in its properties depending upon its use. For catalytic hydrocarbon systems the catalyst may take the form of natural or treated clays, bauxites, inert or active carriers impregnated with certain catalytically active metals or compounds thereof, or synthetic associations of silica, alumina, magnesia, chromia, molybdenum oxide, etc., or combinations thereof to which may be added small amounts of other compounds, usually metallic compounds for specific purposes. When the contact material is employed principally for heat carrying purposes as in pyrolytic conversion processes, it may take the form of any of a number of refractory materials such as fused alumina, mullite, Carborundum, zirconium oxide, charcoal, etc.; for coking processes the solid material may comprise of a low activity clay catalyst, petroleum coke, pumice or similar materials. The contact material may be in the form of pellets, spheres, tablets, pills or irregular shaped material of palpable particulate form as distinguished from powdered material. It should be understood that the term "granular" as employed herein in describing and claiming this invention is intended to broadly cover any of the above forms of contact material. The contact material involved in this invention may range in size from about 0.005 to 0.5 inch and preferably from about 4-20 mesh by Tyler Standard Screen Analysis. The density of the material as poured into a measuring container may be within the range about 20-130 pounds per cubic foot.

In continuous catalytic cracking systems the contact material is passed cyclically through a conversion zone wherein it contacts a hydrocarbon feed at pressures usually above atmospheric and temperatures of the order of 700-1100° F. whereby the feed is converted and then through a regeneration zone wherein a carbonaceous contaminant deposited on the catalyst in the conversion zone is removed by burning. When the granular catalysts are employed it has been found to be highly desirable to maintain the catalyst as a substantially compact bed or column of gravitating particles in the conversion and regeneration zones. Until recently, continuous bucket elevators were employed exclusively to effect transfer of

2

the catalyst between zones in commercial units. Mechanical elevators have been found to impose certain practical limitations on the overall unit height and on the amount of catalyst circulated. As a result, heretofore all commercial continuous catalytic cracking units of the compact moving bed type have involved side by side arrangement of reactor and kiln, thereby requiring two elevators and have involved relatively low catalyst circulation rates. It has been found desirable to increase catalyst circulation rates in order to permit simplification of other parts of the system, particularly the kiln, and to arrange the reactor and kiln in vertical series so as to require only a single catalyst transfer step per cycle. This could not be done practically with existing mechanical transfer devices. It had been proposed from time to time to effect the catalyst transfer by pneumatic transfer lifts but the use of pneumatic transfer in these cyclic conversion systems was prevented because of the very high catalyst attrition and breakage encountered in the pneumatic transfer step, and further because of excessive power requirements. Pneumatic lifts have been developed recently which provide practical pneumatic transfer of the granular contact material in these cyclic conversion systems, in part by delicate control of the gas velocities at various points along the lift. The lifts are disclosed in application for United States Patent Serial Number 210,942, filed February 14, 1951. These lifts involve essentially the use of a continuous vertical lift passage, open at both ends, and with the ends projected into feeding and receiving zones, terminated intermediate the top and bottom of each zone. Contact material is gravitated into the feeding zone at the bottom of the lift as a substantially compact mass and travels downwardly about the lower end of the lift passage. In a preferred form of gas lift, a pneumatic transfer gas is introduced into the zone in two streams, a primary and secondary stream. The primary stream is introduced from a point near the bottom of the lift so as to enter the lift without passing through the mass of compacted material, usually directly beneath the lift. The secondary stream is introduced at one or more locations laterally displaced from the centerline of the lift so that it passes through a substantial thickness of the contact material in the feeding zone. The function of the primary gas stream is to drive the granular solids up the lift pipe into the receiving zone. The function of the secondary stream of lift gas is to regulate the flow rate of solids in the system by forcing solids into the primary gas stream in the lift passage.

It has been discovered that when solids or catalyst velocity in the lift pipe is too low, refluxing occurs and the performance of the lift is unsatisfactory. When the catalyst velocity in the lift is too high, on the other hand, the fountain of solids at the top of the lift in the receiving zone is too high and the performance of the lift is again unsatisfactory. With the catalyst circulation fixed by a definite secondary gas flow rate, the total gas flow controls the catalyst velocity in the lift passage and, consequently, the height of the fountain of particles in the receiving zone at the upper end of the passage. A gas velocity which is too low results in a condition of surge. As the gas velocity is increased, by increasing the primary gas flow rate, the surging stops and the catalyst velocity and the height of the fountain increase.

It has been found that the gas lift will perform best when a condition of mild refluxing, described as incipient refluxing, obtains in the lift passage. It has been discovered that a pressure reading taken at an intermediate level in the lift passage, and preferably the upper two thirds of the passage, can be used to yield a sensitive indication that mild refluxing or incipient surging is occurring, and can be used for operating the lift at peak performance.

The object of this invention is to provide an improved method for operating a gas lift designed to lift granular solids in an upwardly flowing stream of lift gas.

A further object of this invention is to provide an improved method for automatically operating a gas lift which is designed to lift granular solids in an upwardly flowing stream of lift gas at peak performance.

It is a further object of this invention to provide an improved method for pneumatically lifting granular contact material in a cyclic hydrocarbon conversion system with minimum attrition or breakage of the particles.

These and other objects of the invention will become apparent from the following description of the invention, to be read in conjunction with the referenced sketches.

Figure 1 is an elevational view of a preferred arrangement and application of this invention in a cyclic conversion system.

Figure 2 is an elevational view, partly in section, showing a pneumatic lift with gas feeding apparatus and automatic devices for maintaining the lift in operation at optimum performance.

Figure 3 is an elevational view of a gas lift with an alternate arrangement of gas feeding apparatus and automatic devices for maintaining the lift in operation at optimum performance.

Figure 4 is an elevational view of a gas lift showing an alternate embodiment of the invention.

Figure 5 is a typical circular pressure-time diagram obtained by recording the static pressure at an intermediate lift pipe level in an operating moving bed hydrocarbon cracking system for a 24-hour period.

Turning now to Figure 1, there is shown a typical application of this invention in a cyclic continuous moving bed catalytic cracking process. In the drawing there is shown a reactor 10 which is adapted to confine a moving compact bed of catalyst and which internally may incorporate those features by now well known to the art for accomplishing uniform flow, contacting, engaging, and disengaging of the catalyst and reactant. Catalyst enters the reactor through a gravity feed leg 11, which may be of the type disclosed and claimed in United States Patent Number 2,410,309, and catalyst is withdrawn from the reactor via two or more conduits 12 and 13 from which it flows through branch conduits 14 to the upper end of a catalyst regenerator 15. The withdrawal system may be similar to that now disclosed and claimed in United States Patent No. 2,546,625 which issued March 27, 1951. Vaporized hydrocarbon feed, for example, a 500-900° F. gas oil cut, may enter the upper section of the reactor via pipe 17. The feed may be preheated in a heater, not shown, to a temperature of the order of 700-900° F. A suitable high boiling liquid hydrocarbon feed may be supplied into the reactor via pipe 18, either cold or in preheated condition.

The internal liquid feed arrangement may be similar to that disclosed in application Serial Number 719,724, filed in the United States Patent Office on January 2, 1947, now Patent No. 2,574,850. The cracked lower boiling gaseous hydrocarbon products may be withdrawn from the lower section of the reactor via pipe 20. The internal arrangement associated with pipe 20 may be similar to that disclosed and claimed in United States Patents 2,458,498 and 2,459,096. A suitable inert seal gas such as steam or flue gas may be supplied to an upper seal zone in the reactor via pipe 21. The rate of seal gas supply is maintained by differential pressure controller 15 sufficient to control the pressure in the seal zone slightly above that in the reaction zone proper. Similarly, a seal and purge gas is admitted into the lower section of the reactor via pipe 22 to purge gaseous hydrocarbons from the effluent catalyst. It should be understood that the word "gaseous" as employed herein is intended in a broad sense as covering materials in the gaseous phase under the particular operating conditions involved regardless of what may be the phase of such

material under ordinary atmospheric conditions. The reactor may be operated at a pressure near or somewhat above or below that in the kiln. When the reactor pressure is substantially above that in the kiln it may be desirable to provide a depressurizing zone in the legs 12 and 13.

While the invention is not limited thereto the kiln shown is of annular shape so as to provide a central shaft through which a lift conduit 25 extends. The kiln 15 is provided with a central air inlet 26 and flue gas outlets 16 and 19 adjacent either end. A bank of cooling tubes is provided in the lower section of the kiln supplied with a suitable cooling liquid or gas via pipe 27. Cooling fluid leaves these tubes via pipe 28. Suitable internal arrangements for the kiln here shown are disclosed and claimed in application Serial Number 186,953, filed in the United States Patent Office September 27, 1950, now U. S. Patent No. 2,695,220, and Serial Number 186,954, filed in the United States Patent Office September 27, 1950.

The catalyst passes from kiln 15 via two or more pipes 30 and 31 as compact streams delivering onto compact gravity feed legs in pipes 32 and 33, respectively. These legs are vented to the atmosphere on their upper ends, and suitable flow measuring devices may be provided in association therewith.

A lift gas is drawn through the downcomer 50 by means of the blower 51 and delivered under pressure to the heater 52. The blower is driven by the motor 57, the motor speed being controlled automatically by the pressure regulating controller 56 to maintain the blower discharge pressure substantially constant. The lift gas may suitably be air, steam or other inert gas, air being preferred. Fuel is introduced into the heater 52 and burned to heat the air to a temperature near the temperature of the catalyst. The heated air is delivered through the conduit 53 to the primary gas conduit 38 and secondary gas conduit 54. In the preferred form of lift, the primary conduit is projected into the bottom of the lift tank 34 and terminated beneath the lift pipe. The secondary conduit 54 may be split into several conduits 43 distributed about the wall of the tank 34, so that the gas passes through the catalyst bed in tank 34 before entering the lift pipe 25, thereby driving catalyst into the primary gas stream. The combined gas streams lift the particles up the pipe 25 to the separator 36. The gas is withdrawn from the separator 36 through the conduit 63 and the solids are withdrawn through the feed leg 11 to the seal pot 21 and then conveyed into the reactor 10. The dual pressure controller 15 is used to control valve 21 in the inert gas line 55 attached to the seal pot 21, so as to maintain a pressure in the seal pot slightly higher than the pressure in the reactor, thereby preventing the escape of reaction products up the feed leg.

A flow meter 60 is located in the downcomer 50 where it measures the total lift gas flow. A flow regulating controller 61 is operably connected to the flow meter 60 and valve 62 in the primary gas conduit 38, so as to maintain the total gas flow through the lift constant. In this type of gas lift, the flow of catalyst through the lift is determined by the flow rate of secondary gas through the conduit 54. It has been found that the flow of solids is substantially proportional to the pressure at the bottom of the lift. Therefore, a pressure regulating controller 65 is operably connected to a pressure tap 5 at the bottom of the lift and valve 59 in conduit 54, so as to maintain the catalyst circulation substantially constant.

A pressure tap 70 is located in the upper two thirds of the lift pipe and connected to the indicator 79. It has been discovered that this pressure reading can be used to set the gas flow rate for minimum attrition. The gas flow is set above the refluxing rate, i. e., the rate at which violent surging or refluxing in the pipe occurs with sudden changes in pressure and a rapid increase in catalyst break-

age. The gas flow is then reduced gradually by resetting the flow regulating controller 61 until the pressure as indicated on the pressure indicator 79 shows a magnitude of fluctuation of about 100 percent. This is known as the threshold refluxing rate. Any slight further decrease in total gas flow rate would cause the pressure in the pipe as indicated by the indicator to rise 3 or 4 times its normal value and refluxing would be present in the pipe. The flow regulating controller is then set for a flow rate about 1% above the threshold refluxing rate, and the catalyst attrition will be at a minimum value. Broadly, for best performance, the total gas flow rate should be about 0.5-2.0 percent above the threshold refluxing rate and for preferred operation, the total gas flow rate through the lift pipe should be about 0.75-1.25 percent above the threshold refluxing rate.

Referring now more particularly to Figure 2, the catalyst delivers from legs 32 and 33 onto a bed 29 thereof in a lift feed tank 34. A substantially vertical tapered lift pipe 25 extends upwardly from a location within and intermediate the ends of a combination settling—surge vessel 36 which is positioned a substantial distance above the reactor 10. The lower end of the lift pipe may be flared outwardly to form a mouthpiece 35. This mouthpiece is preferably flared outwardly along a curve, approximately a hyperbolic spiral. A detailed view of the mouthpiece is shown on Figure 2. The mouthpiece may be a separate member which is attached to a vertical member to form the assembled lift pipe or may be merely the lower end of a continuous pipe. When the expression "lift passage" is used herein it is meant to include the entire passage from top to bottom including generally a vertical portion and also in preferable designs the curved inlet portion in addition to the vertical portion. The primary gas is introduced through the pipe 38 which terminates directly under the lift pipe above the surface of the mass of solids. The secondary gas is introduced through the pipes 43 into the annular space behind the baffle 47. The secondary gas moves inwardly through the mass of solids about the bottom of the lift pipe into the lower end of the pipe. Preferably the contact material is suspended upwardly from a level below or at least not above the level of primary gas entry.

All the lift gas is passed downwardly through the downcomer 50 to the blower 51. The gas is transferred through the conduit 44 to the heater 52. In order to make the operation more stable a pressure controller 56 is connected to pressure tap 64 in line 44 and used to control the speed of the blower. This is particularly necessary when the blower has a steep performance curve, C. F. M. v. R. P. M. In Figure 2 the controller is used to operate an automatic valve in the steam line supplying steam to a steam turbine used to drive the blower 51. The lift gas, heated in the heater 52, is discharged through the conduit 53 and split into primary and secondary gas streams.

When the velocity of the particles travelling upwardly through the pipe 25 is too low, a refluxing condition occurs in the pipe which may become so violent that flow of solids through the pipe is seriously curtailed or completely stopped. Attrition or breakage of the particles is found to be excessive when refluxing occurs in the pipe. When the velocity of the particles is too high, on the other hand, the particles shoot out of the top of the pipe at excessive velocity and high attrition rates are again encountered. The total gas flow controls the catalyst velocity whereas the secondary gas flow controls the catalyst circulation rate. In starting the lift, therefore, the valve 66 is opened wide enough to provide a total gas flow, as measured by the flow meter 60 in the downcomer 50 which is calculated or known to provide a catalyst velocity above the refluxing rate. The catalyst flow rate is then adjusted by opening the valve 67 in the secondary gas line. It has been found that the catalyst flow rate is related to the pressure drop across the lift. Therefore, when the top of the lift is vented to the atmosphere or the

pressure there is maintained constant, the catalyst flow rate can be maintained constant by means of a pressure controller 68 which is attached to a pressure tap 69 and used to operate the valve 67 automatically. In order that the catalyst attrition be somewhere near the minimum obtainable, the valve 67 is maintained in a fixed position and the total gas flow is reduced by gradually closing the valve 66. The pressure at the bottom of the lift, as indicated by a pressure gauge attached to the pressure tap 69, falls to a minimum value and then with further reduction in total gas flow commences to rise. The lift will give fairly satisfactory performance and reasonably low attrition if operated at the flow rate which yielded the minimum pressure at the bottom of the lift or just slightly above that flow rate. The valve 67 can then be placed on automatic operation to hold the catalyst circulation constant.

It has been discovered that when the gas flow rate is adjusted so that the pressure drop across the lift is at a minimum value, as indicated hereinabove, the attrition of the catalyst in the lift may vary appreciably. It is believed that this lack of uniformity of attrition is caused by variation in gas velocity which are too slight to effect measurable changes in the overall pressure drop and consequently cannot be detected. Experimental operation of a lift pipe designed for commercial operation at a catalyst circulation rate of 360 tons per hour of granular catalyst particles has shown that control of the gas velocity is extremely critical with a three percent increase in velocity causing a twenty-five percent increase in catalyst attrition. A similar decrease in velocity below optimum may even cause more serious difficulty because of the violent refluxing condition which occurs at too low a gas velocity. It has been found that the gas flow rate which provides optimum gas velocity can be determined much more accurately by measuring the static pressure at intermediate points along the lift pipe, preferably at elevations above the bottom third of the pipe. When the gas velocity is too low and refluxing occurs in the pipe, the static pressure rises to about four times its normal value. Excessive velocities cause the static pressure to be depressed. Furthermore, at optimum velocity, fluctuations in static pressure are larger than at excessive gas velocity although they are more uniform and not as violent as those which occur when refluxing is present. Optimum gas velocity is found to occur when the intermediate pressure fluctuations are at their maximum value and yet still of a uniform character. This may be described as a condition of incipient surging or refluxing. If the total gas flow rate is continuously or periodically adjusted to maintain optimum gas velocity in the pipe, as indicated by the intermediate static pressure, the best all round lift performance is obtained and catalyst attrition is at the minimum value.

The gas velocity may be controlled by using the intermediate static pressure as a guide and adjusting the total gas flow rate in accordance with the pressure reading obtained. The gas flow rate is kept low enough to get a maximum width of the pressure band at as high a pressure as possible without having the pressure increase sharply to several times its normal value. The threshold refluxing velocity is determined periodically by lowering the gas flow rate until the static pressure rises rapidly. The gas flow rate is then raised to increase the gas velocity to an incipient refluxing condition. An increase of about one percent over the threshold refluxing rate is found to shift conditions in the lift pipe from refluxing to incipient refluxing. The total gas flow rate can then be adjusted to maintain the intermediate static pressure and/or the width of the pressure band constant.

The gas lift may also be automatically operated at optimum gas velocity continuously. Figure 2 shows a static pressure tap 70 attached to a dampener 71, designed to remove pressure fluctuations. The steady pressure is then applied to a pressure controller 72. Since the optimum gas velocity is very critical, in a preferred form of

the invention the controller is not used to operate the valve 66 but is used to operate the valve 73 in a small by-pass conduit paralleling the main valve 66. Because the gas flow through the by-pass valve 73 is a minor fraction of the flow through the main valve, the valve 73 has sufficient sensitivity to provide close accurate adjustment of the optimum gas velocity. The main valve 66 is set by hand at a flow rate known to be slightly below optimum. The auxiliary valve is then automatically controlled to maintain the velocity at optimum and attrition in the lift at a minimum.

Figure 3 shows an alternate embodiment. The flow meter 60 may be an orifice plate, venturi or other suitable device for measuring gas flow. The heater 52 may be placed in the primary gas line 38, as shown, since the primary gas pipe carries 85-95 percent of the total gas flow, generally. The pressure tap 70 is connected to a limit controller 80 designed to control the width of the pressure band between maximum and minimum ranges. The limit controller is connected to a valve 81 in a small bleed line 82. The bleed line can be arranged to withdraw gas from the primary gas pipe 38 when the valve 81 is opened, or alternatively may admit gas from a pressure source, not shown. By this expedient if the static pressure variation decreases, the gas rate is decreased and vice versa. The optimum variation for any lift pipe is readily determined by a refluxing test and the controller limits set accordingly.

Referring now to Figure 4, an arrangement is shown in which the main valve 66 is operated automatically by a flow controller 83 to maintain a constant flow through the lift pipe 25. A limit controller 84 is connected to the pressure tap 70 and used to operate the valve 73 in line 85, which bypasses the main valve 66. The flow controller 83 has pressure lines 86, 87 on each side of the meter 60 and a by-pass line 88 connecting these lines. Normally, the valve 89 in line 88 is closed. However, the limit controller 84 is designed to automatically operate valve 89 when the valve 73 is operated, such that the pressure drop across the flow meter is not changed. It is also possible to have the limit controller 84 operate directly upon the flow controller 83 to reset the flow meter to a new control point whenever the flow through the by-pass line 85 is increased or decreased. The controller 83 must be changed so that the controlled flow rate is increased or decreased an amount equal to the increase or decrease in the by-pass conduit 85.

As a further embodiment, instead of using a limit controller in the apparatus shown on Figure 3, an automatic sampling instrument can be used to continuously run refluxing tests. The instrument is connected to the pressure tap 70 in place of limit controller 80 and operates valve 81 as shown on Figure 3. The instrument 80' reduces the total gas flow until the lift static pressure rises about 100 percent and then the instrument increases the total gas rate about 1 percent. This series of operations is continuous, keeping the lift gas velocity within an optimum range.

Example

A commercial catalytic cracking system which has reactor superposed the kiln and incorporates a 237-foot pneumatic lift pipe, was operated at a catalyst circulation rate of 340 tons per hour, using a standard cracking catalyst. The lift pipe has a mouthpiece at the bottom which flares outwardly along a hyperbolic spiral curve. The lower frusto-conical section of the pipe extends upwardly about 65 percent of the total length and the upper portion of the pipe is flared outwardly along a smooth curve to a maximum internal diameter of 39.3". The internal diameter of the pipe is 25.65", 27", 29" and 31.7" at the lower end of the frusto-conical section, 50 feet above, 100 feet above and 150 feet above that level. Pressure taps were located at elevations of 166 feet and 214 feet above the bottom of the pipe and readings taken continuously for a 24-hour period. The pres-

sure-time diagrams are shown on Figure 5. During normal operation these pressures were found to fluctuate over a certain band-width around a quite constant average value. The time of fluctuation from one edge of the band to the other averaged about one a minute. When the primary air flow was decreased the band was enlarged and the average value shifted in the direction of higher pressures. On further decrease in primary air flow, refluxing occurred, as evidenced by the momentary pressure increases to values extending outside, and on the high side of, the bands of normal operation, such as shown at points A, B, C, D and E on the pressure diagram of Figure 5. During the period from 1:00 p. m. to 7:00 p. m. the air flow was varied, as indicated on Figure 5, to show the difference in pressure-time diagram at different gas rates. When operated continuously at incipient refluxing conditions, such as indicated on the Figure 5 between 7:00 p. m. and 9:00 a. m., the attrition rate was less than one and one-half tons per day for a circulation rate of 340 tons per hour. The gas flow for minimum attrition, at the operating conditions obtaining, was about 12,600 s. c. f. m. The threshold refluxing rate was found to be about 12,475 s. c. f. m.

It is to be understood that the specific examples of apparatus, design and arrangement, and of operation and application of this invention are intended only as illustrative of the invention and it is intended to cover all changes and modifications of the example herein chosen for purposes of disclosure, which do not constitute departure from the spirit and scope of the invention.

We claim:

1. In a hydrocarbon conversion process in which a granular solid is gravitated as a substantially compact columnar mass through reaction and regeneration zones and lifted from a location below one of the zones to a location above the other zone through an upwardly directed lift passage by means of a flowing stream of lift gas, the improved method of controlling the lifting step for optimum performance with minimum attrition which comprises: gravitating granular solids downwardly from the bottom of one of the zones to a feeding zone located at the bottom of the lift passage, introducing a lift gas into the feeding zone, so as to support and transport the granular solids upwardly through the lift passage, measuring continuously the static pressure in said passage at a location in the upper two thirds of the passage, and controlling the flow rate of the lift gas admitted to said feeding zone in response to said static pressure, so that the flow is maintained below that point at which minimum pressure occurs and slightly above that point at which the pressure increases very substantially with any further reduction in gas flow rate, whereby the attrition of the granular solids during transfer through the lift passage is minimized.

2. In a hydrocarbon conversion process in which a granular solid material is gravitated as a substantially compact columnar mass through reaction and regeneration zones and lifted from a location below one of the zones to a location above the other zone through an upwardly directed lift passage by means of a flowing stream of lift gas, the improved method of controlling the lifting step for minimum attrition of the solids which comprises: gravitating granular solids downwardly from the bottom of one of the zones to a feeding zone located at the bottom of the lift passage, so as to form a substantially compact bed of solids about the lower end of the passage, measuring the flow of a stream of lift gas, splitting the stream of lift gas into primary and secondary gas streams, and controlling the flow rate of the primary gas stream in response to change in the measurement of total gas flow to maintain the total gas flow substantially constant, introducing at least the major portion of the primary gas into the feeding zone, so as to enter the lift passage without passing through any substantial thickness of the solids bed in said feeding zone, intro-

ducing the secondary gas into the feeding zone, so as to pass through a substantial thickness of the solids bed before entering the lift passage, continuously measuring the static pressure at the bottom of the lift passage and controlling the flow rate of the secondary gas, in order to maintain said static pressure at the bottom of the lift passage substantially constant, continuously measuring the static pressure in the lift passage at a location in the upper two thirds of the passage, bleeding a minor proportion of the primary gas stream out of said stream at a point intermediate the point at which said stream is controlled in response to total gas flow indication and the point at which said primary gas stream enters the lift passage, and controlling the flow rate of the bleed stream in response to the static pressure indication in the upper two thirds of the lift passage, so as to maintain said static pressure below the threshold refluxing pressure and above the minimum pressure, whereby the breakage of particles during transfer through the lift passage is minimized.

3. In a hydrocarbon conversion process in which a granular solid material is gravitated as a substantially compact columnar mass through reaction and regeneration zones and lifted from a location below one of the zones to a location above the other zone through an upwardly extending lift passage by means of a flowing stream of lift gas, the improved method of controlling the lifting step for minimum attrition of the solids which comprises: gravitating granular solids downwardly from the bottom of one of the zones to a feeding zone located at the bottom of the lift passage, so as to form a substantially compact bed of solids about the lower end of the passage, measuring the flow of a stream of lift gas, splitting the stream of lift gas into primary and secondary gas streams, and controlling the flow rate of the pri-

35

mary gas stream in response to change in flow rate of the total gas flow to maintain the total gas flow substantially constant at a predetermined flow rate, introducing at least the major portion of the primary gas into the feeding zone, so as to enter the lift passage without passing through any substantial thickness of the solids bed in said feeding zone, introducing the secondary gas into the feeding zone, so as to pass through a substantial thickness of the solids bed before entering the lift passage, measuring the static pressure at the bottom of the lift passage and controlling the flow rate of the secondary gas, in order to maintain the static pressure at the bottom of the lift passage substantially constant, whereby the flow rate of solids through the lift is maintained substantially constant, measuring the static pressure in the lift passage at a location in the upper two thirds of the passage, and changing the predetermined flow rate at which the total gas flow is maintained an amount sufficient to maintain said static pressure substantially constant, said constant pressure value being below the threshold refluxing pressure and above the minimum pressure, whereby particle attrition during transfer through the lift passage is minimized.
